UNITED STATES PATENT OFFICE.

ROBERT CRAIG, OF DAYTON, OHIO, ASSIGNOR TO DAYTON SCALE COMPANY, OF DAYTON, OHIO, A CORPORATION OF NEW JERSEY.

SCALE CASING.

Application filed August 25, 1923. Serial No. 659,415.

This invention relates to improvements in casings for weighing scales and the like.

At the present time there is a considerable demand for weighing scales having a porcelain finish. Such scales are considered to be more sanitary than the ordinary enamelled or painted scales, since porcelain surfaces not only do not tend to accumulate dirt to as great an extent as enamelled or painted surfaces. Furthermore, the porcelain surfaces can be more readily cleaned.

In the manufacture of such scales it has been found that there is a tendency for the porcelain surfaces to chip at junction points and under retaining screws. In addition, the porcelainining of the parts tends to warp the same and also the procelain surface itself is slightly wavy so that extreme difficulty is encountered in fastening adjacent parts together. These considerations have heretofore prevented the use of sheet metal and necessitated the use of castings for various parts formerly made of sheet metal. The use of such castings not only add to the expense but also necessitate complicated fastening devices which usually cause chipping of the porcelain surfaces.

The present invention is directed to the provision of a scale casing of such form that porcelainined surfaced sheet metal stampings may be employed without the attendant objections heretofore experienced.

In the drawings,

Fig. 1 is a front view of the upper part 35 of a drum scale.

Fig. 2 is a sectional view taken on line 2-2 of Fig. 1.

Figs. 3 and 4 show details of construction.

In more detail, 10 has a casting forming 40 the pedestal of the scale. This casting has branched upper portions 11 suitably machined at 12 to receive the drum portion of the casing. 13 are frames, one at each end, which are secured by screws to the pedestal casting. These frames support the working parts of the scale, not shown.

The drum casing comprises two sheet metal plates 14, 15, having a substantially semi-circular contour (see Fig. 2) and provided with reading openings, one being shown at 16 and the other below the projection 17. The plates 14 and 15 have lower lip portions 18, which fit between the frame 13 and the pedestal as shown in Fig. 2. 55 They are also provided with upper shoul-

dered portions 19 which receive fastening screws 20 which hold the two plates together and into firm contact with the ring 13. The front reading opening is covered with a box-like member 21 carrying the usual magnifying glasses 22. This part is secured to the plate 14 by screws 23.

Covering the upper junction of the two casing plates is a channel like sheet metal member 24, which, at its ends, has tongue portions 25 (Figs. 3 and 4). These tongue portions are projected downwardly so as to lie in the same plane with the upper edges or corners 26-27 of plates 14 and 15.

After the cover plates 14 and 15 are assembled and the channel 24 is placed in position, a pair of flanged end caps 28 are passed over the end plates 14 and 15, and the tongues 25. These caps are secured in position by suitable screws not shown and may be provided with glass covered openings 29. The end caps also have depending portions 30 with suitable shoulders or flanges to engage over the ends of branches 11 of the pedestal casing.

In practice, it has been found that certain junction points in the casing are particularly noticeable when the parts are porcelainined.

To prevent the unsightly appearance of such linear junction points, I provide struck-up beading formed directly in the sheet metal. This beading is shown at 31. The beading, which extends adjacent to and parallel with the linear junctions, to an observer appears to be a part of the design of the casing, but in reality it serves to obscure the wavy porcelain junction points.

What I claim is:

1. In a casing for a weighing scale, in combination, with a supporting pedestal, of a drum casing therefor comprising a pair of substantially semi-circular sheet metal plates having shoulders at one end to receive fastening devices for drawing said plates toward one another, a channel like cover for said plate junction, said cover having projecting portions disposed substantially in the plane of said plates, and end caps having flanges engaged over the ends of said plates and projecting portions.

2. A weighing scale casing having two cooperating casing parts comprising a sheet metal plate and a supplementary attached part, said parts and plate abutting at sub-

stantially right angles to each other and having a linear junction, and means in said sheet metal plate for obscuring the junction of said part and plate, said means including a beading struck up from the metal of the plate and adjacent the said junction.

3. In a weighing scale having a multiplicity of cooperating parts including sheet metal plate-like casing parts and other parts abutting thereagainst and having surface portions extending substantially perpendicularly with respect to the plane of surface of said plate-like parts, and beading in said casing parts adjacent to and substantially parallel to the junction between the parts for the purpose described.

4. A weighing scale casing including a pedestal, a pair of ring-like frames spaced apart and supported upon said pedestal, a pair of substantially semicircular sheet metal casing members having upturned shouldered portions at one end thereof and lip portions at the other end thereof, said lip portions being fitted between the frame portions and the pedestal, adjustable fasten-

ing devices serving to draw the upper shouldered portions together, and a cap placed over said upper shouldered portions and spaced therefrom substantially as described.

5. A weighing scale casing comprising two substantially semicircular sheet metal portions having snouldered portions at one end thereof and fastening screws passed therethrough for drawing said shouldered portions together and securing said sheet metal portions in position upon the scale, a cap member disposed over and spaced from said shouldered portions and being supported directly upon said sheet metal semicircular portions of the casing, a pair of end rings fitted over the ends of said sheet metal portions, said rings also extending over lip members extended from the ends of said cap portion whereby said end rings serve to hold said cap portion in position upon the sheet metal portions.

In testimony whereof I hereto affix my signature.

ROBERT CRAIG.
